UNITED STATES PATENT OFFICE.

ALBERT M. ANDERSON, OF MILWAUKEE, WISCONSIN, ASSIGNOR OF ONE-HALF TO
JOHN W. THOMAS, OF CHICAGO, ILLINOIS.

RAILWAY MUD-GUARD.

1,244,010.

Specification of Letters Patent. Patented Oct. 23, 1917.

Application filed March 10, 1917. Serial No. 153,880.

To all whom it may concern:

Be it known that I, ALBERT M. ANDERSON, a naturalized citizen of the United States, residing at Milwaukee, in the county of 5 Milwaukee and State of Wisconsin, have invented certain new and useful Improvements in Railway Mud-Guards, of which the following is a specification.

My invention relates to railway mud 10 guards for use at highway crossings, etc., and one object is to provide a comparatively simple and inexpensive device of this character that can be installed at low cost, and in which the cost of maintenance is reduced 15 to a minimum.

A further object is to provide substantial 20 supporting means whereby the track rail and the abutting mud guard rail are reliably held in proper relation to each other, so that 25 one cannot move independently of the other and leave a dangerous opening between said rails.

Other objects of the invention will hereinafter appear, and in order that said invention may be fully understood, reference 30 will now be made to the accompanying drawing, in which:

Figure 1 is a broken, plan view of a highway crossing at a section of track in which 35 my devices are installed.

Fig. 2 is an enlarged cross section on line II-II of Fig. 1.

Fig. 3 is a cross section, enlarged, on line III-III of Fig. 1.

Fig. 4 is a detail, perspective view of the preferred form of device.

Fig. 5 is a detail of a modified form of device.

Referring now in detail to the various 40 parts, A designates the track rails, B the mud guard rails which are turned over upon their sides, and C the underlying cross ties.

1 designates my device which embodies a base plate 2 and a supporting member 3 45 which may be either cast integral with said base plate 2 or made separate therefrom, as disclosed by Fig. 5. The base plate 2 is provided at opposite sides with spike holes 4, through which spikes D may be driven 50 to firmly secure said base plate upon a cross tie C, and also assist in securing the track rail A upon the base plate.

The top of the supporting member 3 is formed to snugly fit the abutting side of the 55 guard rail B, to constitute a seat therefor,

the raised, central portion 5, being adapted to fit against the web F, while the lower, grooved portions 6 and 7 snugly fit the ball G and the base flange H, respectively, of said guard rail B. The base flange H of 60 the guard rail B is further engaged by a lip 8, extending upwardly from one side of the supporting member 3 and constituting the outer wall of the groove 7. The outer wall of the groove 6 also extends upwardly 65 and constitutes a marginal flange 9, which projects upwardly a slight distance between the ball of the guard rail B and the abutting side of the track rail A.

The supporting member 3, in addition to 70 reliably holding the guard rail B in position, coacts with a number of spikes D in holding the track rail A down upon the base plate 2, said member 3 having a wall 11 which overlaps the rail base I and extends 75 upwardly against the adjacent web of the rail where it communicates with the lip 9 as disclosed by Figs. 3 and 4.

In practice, when the parts are assembled 80 as disclosed by Figs. 1, 2 and 3, the ball of the guard rail B is reliably held by the supporting member 3 against the web and beneath one side of the ball of the track rail A, and thus overcomes vertical and lateral 85 stresses tending to force said rails from their proper relative positions. The member 3 is aided in holding the rails A and B in proper position by the base plate 2, which carries said member 3 and also the rail A, so that said rail cannot move vertically independently of the member 3 and the rail B. The usual planking E is laid between the track rails and at the outer sides thereof as disclosed by Figs. 1 and 2.

From the foregoing description, it will be 95 understood that the rails A and B cannot be forced apart to leave an opening for mud and other foreign matter to wash in between the same, or wherein a horse is likely to catch the calks of his shoes and thus break a 100 limb, which sometimes occurs where the old type of installation is employed. The present invention also provides a comparatively smooth surface for vehicles crossing the track as the guard rail B cannot move upwardly or downwardly from its relative position to the upper surface of the track rail A and the abutting planks E, the margins of which are protected from splintering and undue wear, by the upper edges J of the base 105 110

of the rails B, as said upper edges extend to a level with the upper surface of said margins. Said margins also rest upon the lips 8 and are prevented thereby from being depressed below the upper edges J of the guard rails B.

In the modified form disclosed by Fig. 5, the supporting member 3^a is made separate from the base plate 2, but in other respects 10 is the same as the supporting member 3.

Having thus described my invention, what I claim and desire to secure by Letters Patent, is:

1. In combination with a track rail and a 15 mud guard rail which latter is disposed upon its side with its ball engaging the web and the ball of the track rail, a member having a seat for the ball of the mud guard rail and a wall overlapping the base flange and abutting the web of the track rail to hold the 20 two rails in their proper positions, substantially as described.

2. A device of the character described, 25 consisting of a supporting member having a raised central portion adapted to fit against the web of a guard rail laid upon its side, and grooves at opposite sides of said raised central portion to constitute seats for the ball and the base flange of said guard 30 rail.

3. A device of the character described, consisting of a supporting member having a

raised central portion adapted to fit against the web of a guard rail laid upon its side, 35 grooves at opposite sides of said raised central portion to constitute seats for the ball and the base flange of said guard rail, a lip constituting one wall of one of said grooves, and a flange constituting one wall of the other groove.

4. In combination with a track rail and a mud guard rail which latter is disposed upon its side with its ball engaging the web and the ball of the track rail, a base plate to underlie said rails, and a member on said 40 base plate to engage both rails and hold them in proper relation to each other.

5. A device of the character described, 45 consisting of a base plate, a supporting member having a raised central portion adapted to fit against the web of a guard rail laid upon its side and having grooves at opposite sides of said raised central portion to constitute seats for the ball and the base flange of 50 said guard rail, a lip constituting one wall of said groove, and a flange constituting one wall of the other groove, substantially as described.

In testimony whereof I affix my signature, in the presence of two witnesses.

ALBERT M. ANDERSON.
